Patented Dec. 2, 1919.

UNITED STATES PATENT OFFICE.

CORNELIUS MADSEN, OF CHICAGO, ILLINOIS.

UPHOLSTERY.

1,323,370.

Specification of Letters Patent.

Patented Dec. 2, 1919.

Application filed August 28, 1919. Serial No. 320,341.

To all whom it may concern:

Be it known that I, CORNELIUS MADSEN, a citizen of the United States, and a resident of Chicago, in the county of Cook and 5 State of Illinois, have invented certain new and useful Improvements in Upholstery; and I do hereby declare that the following is a full, clear, and exact description thereof, reference being had to the accompanying drawings, and to the characters of reference marked thereon, which form a part 10 of this specification.

This invention relates to improvements in upholstery and refers more particularly to 15 upholstery for furniture, such as car seats, couches, chairs, and the like, wherein the upholstery structure embodies a roll-edge.

The object of the invention is to provide 20 an upholstery structure having a novel roll-edge so constructed as to produce a firm and reliable edge in a simple and economical manner.

Another object of the invention is to provide 25 a roll-edge upholstery structure which is combined with the spring panel of the structure in such a way as to firmly connect the roll-edge to the frame from an underneath support.

Other objects of the invention are to improve, 30 simplify, and reduce the cost of roll-edge upholstery structures, and the invention consists in the combination and arrangement of the parts shown in the drawings and described in the specification, and 35 is pointed out in the appended claims.

In the drawings:

Figure 1 is a fragmentary edge view of 40 an upholstery structure having a roll-edge embodying my invention, with parts broken away.

Fig. 2 is a fragmentary bottom view thereof.

Fig. 3 is an enlarged cross section on the line 3—3 of Fig. 1.

Fig. 4 is an enlarged fragmentary section on the line 4—4 of Fig. 3.

In said drawings, 10 designates a panel usually made of wood and of a shape to conform to the edge of the seat or other 50 furniture part in which the upholstery is embodied. Said panel is preferably enclosed in a sheath or envelop 11. The panel constitutes in effect the foundation of the roll-edge and the adjacent part of the upholstery structure, and is directly supported 55 on springs 12 which, in the complete article

or furniture are seated on a suitable fixed support below.

14 designates a web or canvas or other fabric which overlies the covered panel 10. 60 It extends inwardly beyond the panel to constitute a portion of the foundation fabric for the seat or other article of furniture in which the upholstery is embodied. It also extends, as herein shown, outwardly 65 beyond the panel to constitute an apron or border piece 15 that depends from the front edge of the panel below the roll-edge.

16 designates as a whole the roll-edge embodying the invention which is built on 70 and fixedly attached to the panel. Said roll-edge embraces in its construction a rigid reinforcing bar 17, preferably made of metal and spaced above the panel board. Said roll-edge comprises, in addition to said 75 bar 17, a body or core 18 of cushioning material, such as felt, hair, or like material, which is shaped to produce the desired cross section of the roll-edge, and inner and outer cover layers 19, 20, which may 80 respectively be made of burlap and canvas.

The reinforcing bar 17 is embedded in the core material 18, it lying near the lower side of said core material. The lower marginal part 21 of the outer or canvas cover 85 layer lies over the covered panel 10 and may be attached, as by means of tacks 22, to said panel. Said outer cover layer 20 extends around the roll-edge and its inner marginal portion fits downwardly over the 90 inner side of said roll-edge, as shown in Fig. 3 and extends at its extreme inner margin 23 inwardly beyond the roll-edge. The lower marginal portion of the inner burlap cover layer 19 for the core 18 of the roll- 95 edge lies between the marginal portion 21 of the outer cover layer 20 and that part of the core material which lies below the reinforcing bar 17. Said inner cover layer 19 extends around said core 18 with its inner 100 margin 24 extending inwardly beyond said reinforcing bar and in overlapping relation to the marginal portion 23 of the cover layer 20 and between it and the lower marginal portion 21 of said cover layer 20.

The reinforcing bar may be inclosed by one or more layers 25 of suitable fabric, such as burlap, said layers extending from the inner edge of said bar around the outer edge and thence over the top of the bar, 110 with the inner marginal portions 26 thereof lying between the fabric 14 and the mar-

ginal portions 23, 24 of the cover layers 19, 20, respectively.

The drawing shows a fragment of upholstery embodying my improved roll-edge, which comprises one corner of a furniture part, and, therefore, shows the curved portion of the panel between the right angle members thereof. The reinforcing bar 18 lies parallel to the panel and is of the same shape as the panel.

10 The said panel is attached to the reinforcing bar by metal fastening devices which extend through both said parts and are clenched over the bar. As herein shown, said metal fastening devices have the form of wire staples 27, the closed parts of which may be made of substantial length and lie underneath the panel 10. The arms 28 of said staples extend through the overlapping portions of the panel, the lower marginal portions of the inner and outer cover layers 19 and 20, through a portion of the filling body or core 18 and through the reinforcing bar 17. The terminals of said arms 28 are 25 folded over the top of said reinforcing bar in the manner shown in Fig. 4.

15 The inner side of the roll-edge is finished by a row of stitching 29 which passes through the margins 23 and 24 of the inner and outer cover layers of the roll edge, 30 through the marginal portions 26 of the cover for the reinforcing bar and through the foundation fabric 14 so as to firmly bind the several margins to the foundation piece, 35 and also serves in coaction with the staples to hold the reinforcing bar in place.

20 The construction described produces a roll-edge for upholstery structures which is in itself firm and which, in combination 40 with the means for fastening it to the foundation panel, is a secure part of the upholstery as a whole.

I claim as my invention:

1. In upholstery, a roll-rim comprising, 45 in combination with a panel, of a padded rim, a reinforcing bar embedded therein, and means to fixedly attach said panel to said bar.

2. In upholstery, a roll-rim comprising, 50 in combination with a panel, of a padded rim thereover, a reinforcing bar embedded therein, and staples extending through said panel and bar and clenched over the latter.

3. In upholstery, a roll-rim comprising a 55 padded rim, a cover layer formed about the

rim with its margins stitched together inwardly beyond the rim, a reinforcing bar embedded in the rim, and a flexible cover therefor stitched to the rim.

4. In upholstery, a roll rim comprising a 60 padded rim, a cover layer formed about the rim with its margins extending inwardly beyond the rim, a reinforcing bar embedded in said rim, and a flexible cover for said bar having its margin extending inwardly 65 between the margins of the cover layer and stitched thereto.

5. In upholstery, the combination with a 70 panel, and a foundation fabric overlying said panel and extending inwardly therebeyond, of a padded rim over said panel, a cover layer for said rim having its margins extending inwardly beyond the rim over said foundation fabric, a reinforcing bar, and a cover therefor, having its margin between 75 said cover layer margins and stitched thereto and to said foundation fabric.

6. In upholstery, the combination with a 80 panel, and a foundation fabric overlying said panel and extending inwardly therebeyond, of a padded rim over said panel, a cover layer for said rim having its margins extending inwardly beyond the rim over said foundation fabric, a reinforcing bar, a cover therefor, having its margin between 85 said cover margins and stitched thereto and to said foundation fabric, and means to fixedly fasten said panel to said reinforcing bar.

7. In upholstery, a roll-rim comprising, 90 in combination, a panel, a rim superposed on said panel comprising a cushion core, a cover therefor, having its margins stitched together at the inner side of the rim, a reinforcing bar within said core, and means 95 95 piercing said panel and bar to fixedly fasten them together.

8. In upholstery, a roll-rim comprising, 100 in combination a panel, a rim superposed on said panel comprising a cushion core, a cover therefor, having its margins stitched together inwardly beyond said rim, a reinforcing bar within said core, and staples 105 extending through said panel and bar and clenched over the latter.

In witness whereof I claim the foregoing as my invention, I hereunto append my signature this 22d day of August, 1919.

CORNELIUS MADSEN.
